UNITED STATES PATENT OFFICE

HERBERT MAYLED, OF BATAVIA, NEW YORK, ASSIGNOR TO THE R. E. CHAPIN MFG WORKS, OF BATAVIA, NEW YORK

METAL RECEPTACLE

Application filed January 6, 1928. Serial No. 244,851.

This invention relates to improvements in cans or receptacles, such, for example, as are used for dispensing gasolene, oil or other liquids from tank wagons, and at garages and 5 automobile filling stations for handling gasolene and oils. These cans, which are commonly made in five gallon and larger sizes, are quite heavy when filled and must be of very strong and sturdy construction to successfully withstand the rough usage to which 10 they are liable to be subjected, they being frequently dropped on the ground and thrown or knocked about so as to become badly battered and caused to leak. It has been attempted to strengthen such cans by 15 external reinforcing hoops or bands at the upper and lower ends of the cylindrical body portions of the cans, but such hoops are frequently dislodged or broken in the rough handling of the cans, and if the cans are made, as they usually are, with soldered or lock seam joints such as ordinarily employed in lighter or smaller sheet metal receptacles, the external reinforcing bands do 20 not give the necessary protection and the cans soon become so badly battered as to open the joints and cause the cans to become leaky to an extent to render them useless.

One object of my invention is to produce 30 a strong and durable heavy duty can or receptacle of the sort mentioned, which is of a novel construction such as to adapt the can to withstand the rough usage to which such cans are liable to be subjected.

Other objects of the invention are to provide 35 the can with a neck disposed eccentrically so that the contents can be readily and quickly poured from the can into a receiving receptacle without spilling or wasting the contents, and to form and join the neck to the shoulder portion of the can so that the neck and the joint between the same and the body will not be battered or injured by striking 40 the neck forcibly against an object or supporting the weight of the can and its contents by resting the neck on an object when emptying the can; also to connect the shoulder portion and bottom of the can to the cylindrical body member by reinforced welded joints which will be strong and durable and

will not be opened up or broken by the rough handling or dropping of the can; also to reinforce the can at the joints between the body and the bottom and shoulder members by means of internally arranged bands which 55 cannot be displaced by the dropping or rough handling of the can and which are welded to the adjoining parts of the can; also to provide the can with a rigidly attached handle so disposed with reference to the eccentric neck of the can that the can will balance 60 properly from the handle and can be comfortably carried when full by means of the handle without liability of striking the bottom of the can against the ground or splashing 65 the contents out of the can; and also to improve the construction of metal cans of the sort mentioned in the other respects herein-after described and set forth in the claims.

In the accompanying drawings:

Fig. 1 is a side elevation of a can embodying my invention.

Fig. 2 is a vertical, sectional elevation thereof with the cover removed.

Fig. 3 is a plan view thereof.

Fig. 4 is an enlarged section showing the reinforced joint construction between the bottom and body members of the can.

Fig. 5 is an enlarged section showing the construction of the neck and the joint between the same and the body.

Fig. 6 is an enlarged section of the reinforced joint between the body and shoulder members of the can.

The can is composed of a substantially 25 cylindrical, open ended member 1, a bottom 2 and a shoulder member or portion 3 which are preferably made of galvanized sheet metal of suitable gage, and a neck 4 which preferably consists of a section of seamless 30 steel tubing of heavier gage than the galvanized sheet metal of which the body of the can is constructed. These parts are all integrally united by strong welded joints, preferably formed by oxyacetylene welding.

The bottom 2 of the can, which is preferably outwardly convexed, is formed with a downwardly projecting cylindrical peripheral flange 5, and this flanged bottom is seated within the lower end of the cylindrical body

member 1 against an internal circumferential shoulder 6 on the body member. This shoulder 6 is preferably formed by an integral inbent bead or corrugation on the body member. The peripheral flange 5 of the bottom 5 fits snugly within the lower end of the cylindrical body member with the external face of the flange 5 contacting with the internal face of the body member. The shoulder or bead 6 10 forms a stop against which the bottom is seated and which thus serves as a gage to fix the position of the bottom when assembling the parts. Fitting inside of the flange 5 of the bottom is a cylindrical reinforcing hoop 15 or band 7 which is preferably made of a heavier gage metal than that employed for the body and bottom members. This band 7 fits snugly within the bottom flange 5 with its upper edge bearing against the exterior surface of the bottom 2 and its lower edge 20 substantially flush with the lower edges of the body member 1 and bottom flange 5. When these three parts have been assembled in this relation, they are all welded together, 25 preferably at their bottom edges, as indicated at 8, see Fig. 4. The three parts are thus united in an integral, unitary structure which insures a very strong and reliable joint between the bottom and the body. Since the 30 can bottom 2 abuts against the internal shoulder 6 on the body member and the reinforcing band abuts against the external surface of the bottom, the bottom and band are prevented from being forced upwardly or inwardly out of place, and this construction 35 in conjunction with the welding of the bottom edges of the three parts to each other, makes a very strong and reliable union and insures that the joint will not be broken or 40 the parts forced out of place by any blows to which the parts may be subjected in the use of the can. By this arrangement also, the reinforcing band 7 is enclosed and protected by the surrounding integral portions 45 of the body and bottom and cannot be dislodged or displaced as in the case of an external hoop or band. The internal arrangement also avoids the objection to the external reinforcing band, in that the band does 50 not form an external shoulder on which liquids or dirt can lodge.

The shoulder member or portion 3 of the can is preferably of oblique frusto-conical formation, and is secured to the upper edge 55 of the cylindrical member 1 of the can, preferably as follows, see Fig. 6 of the drawing.

The large bottom end of the shoulder member 3 is preferably formed with an outwardly extending peripheral flange 10 adapted to 60 bear upon the upper edge 11 of the body member 1. The body member 1 is also provided below its upper edge with an internal circumferential shoulder 12, preferably formed by an integral, inbent bead or corrugation 65 on the body, and a reinforcing band

13, preferably of heavier gage metal than the body 1 is fitted within the upper end of the body with its lower edge abutting against the internal bead 12 and its upper edge substantially flush with the upper edge 11 of the body member 1. The flange 10 of the shoulder member 3 of the can abuts against the upper edges of the body member and the reinforcing band 13, and these three parts are welded together as indicated in Fig. 6, 70 preferably by oxyacetylene welding. This formation produces a very strong, durable and reliable joint between the shoulder and body members of the can. The upper reinforcing band 13 is held from endwise displacement by engagement at its opposite edges with the internal bead 12 and the contracted shoulder member 3 of the can so that aside from the welded connection between the upper edge of the band and the body and shoulder members, the band cannot be displaced by blows against the can and, as in the case of the bottom reinforcing band 7, the band being located internally of the can, does not form an external shoulder against which 75 objects could strike and on which liquid or dirt could lodge.

The seamless tube neck 4 of the can is preferably provided with a rabbeted lower edge 80 14 in which the upper edge of the shoulder member 3 of the can is seated and is secured by welding these edges together, as indicated in Fig. 5 of the drawings. The neck 4 is appropriately grooved or shaped at its upper 85 end to afford the required hold for the cover or can closure device.

15 represents the handle for carrying the can. This handle is rigidly secured to the upper or shoulder portion 3 of the can by riveting or in any other suitable manner, and is preferably located so that the legs of the handle extend at an inclination, straddle the neck 4 and are secured to the can substantially in the vertical central plane of the can while the cross bar of the handle is disposed at the inner side of the eccentrically located neck 4. By this location of the handle, the can, when filled and carried by the handle 105 will hang or balance in nearly vertical position and, therefore, the can is adapted to be readily carried without danger of striking the lower end of the can against the ground and, due to the nearly upright position of the can, the same can be carried full, without serious danger of the contents splashing from the mouth of the can and being wasted. The handle in this location is also protected by the strong rigid neck 4 of the can from injurious 110 knocks.

The cylindrical body of the can is preferably provided near its upper and lower ends with outwardly projecting circumferential corrugations 16 which serve to further stiffen and strengthen the body and also to form cir- 115 120 125 130

cular projections on which the can is adapted to be rolled on its side.

I claim as my invention:

1. A metal can comprising a tubular shell, an upwardly contracting top end wall fitted across and closing the top end of the shell, and an internal reinforcing band fitted peripherally around and against the interior of the shell below and against the bottom face of said top end wall, said band, shell and top end wall being welded together at the junction between the top end wall and said shell.
2. A metal can comprising an internal shell of sheet metal having a portion thereof deformed inwardly to provide an inwardly projecting stop at a point adjacent but spaced a short distance below the upper open end of the shell, a reinforcing band fitted peripherally around and against the interior of the shell, extending from the upper open end downwardly to said stop, and supported by said stop, and a top end wall of sheet metal fitted across and against the top edges of the shell and said reinforcing band and closing the upper end of said shell, said shell, top end wall and band being welded together at the junction between the shell and top end wall.
3. A metal can comprising a shell of sheet metal open at its upper end, an internal reinforcing band fitted peripherally around and against the interior of the shell, with its upper edge substantially flush with said open end of the shell, a frusto-conical top end wall of sheet metal having an outwardly extending flange around its larger end resting upon the upper end of said shell and the upper edge of said band, said shell, band and flange being welded to one another at their junction, and said top end wall rising from said shell and terminating in a filling and discharging neck.

HERBERT MAYLED.
